WRAPPING MACHINE

Henry L. Byland, Deerfield, Ill., assignor to U.S. Slicing Machine Company, Inc., La Porte, Ind., a corporation of Indiana

Application April 25, 1957, Serial No. 655,053

22 Claims. (Cl. 53—230)

This invention relates to a wrapping machine for wrapping edible foods, such as poultry, fresh meats, produce, cold meats and cheeses, on boards, cards, pans or trays to fashion a tightly wrapped, neat, heat-sealed package, especially for selling foods on self-service counters in supermarkets, although other uses and purposes may be apparent to one skilled in the art.

The present invention comprises, in general, a machine for prepackaging foods on trays or cards to form tightly wrapped, heat-sealed packages. Manually, a sheet of wrapping material is arranged over a tray or card in tubular fashion and tack-sealed on the bottom in a manner heretofore well known and what constitutes the first step of the well known "diamond wrap" or "square wrap." The tray is then placed at the infeed side of the machine with the axis of the flaps extending normal to the direction of feed. A conveyer advances the package through a tucking and folding unit which tucks the side flaps and effects a downward folding thereof while the package is being moved therethrough by the conveyer. From the tucking and folding unit, the package is advanced into a side and bottom sealer unit which grasps the downwardly folded side flaps, draws them tightly underneath the bottom of the package, heat-seals the folds of the flaps and a portion of a flap beneath the bottom of the package. A second conveyer advances the package over a bottom V-shaped folder which folds the remaining portions of the flaps against the bottom of the package before it is advanced over a heat-sealer bar and is discharged to a receiving table for further distribution.

An important feature of the invention is the tucking and folding unit which includes a front tucker for tucking the leading edges of the flaps, a rear tucker for tucking the trailing edges of the flaps, upper and lower overlapping folding plates for folding the flaps downwardly, and a set of auxiliary feed rolls for advancing the lower ends of the flaps faster than the conveyer can travel to assure the substantial centering of the flaps with respect to the package. A pair of gathering rollers are mounted ahead of the tucking unit for holding down the flaps on high packages and guiding the flaps into the folding plates. This arrangement is unique, since the tucking and folding operations are accomplished while the package is in motion as it is being advanced through the folding and tucking unit.

It is also an important feature of the invention to provide a tightly wrapped package which may be achieved by the side sealing unit into which the package is conveyed after it leaves the folding and tucking unit. The side flaps are sealed, stretched around the package and partially sealed to the bottom of the package before being advanced to the bottom folder and sealer.

A further important feature of the invention is in its versatility to wrap loaded trays or pans of varying heights and widths and loaded cards or boards of various widths, wherein the width adjustment may be accomplished by a single control.

2

Wrapping machines developed heretofore have necessitated the use of reciprocating members to effect the downward folding of the side flaps thereby necessitating such an operation to be performed at a rest station. For example, one known wrapping machine employs an elevator to raise the package between opposed members and push down the side flaps, while another known wrapping machine employs vertically movable folding plates which drop along the side of the package and pull down the end flaps. Whenever an operation is performed on an item at a rest station, as explained in these examples, the period of time for the entire wrapping operation is prolonged. Further, known machines are objectionable from the standpoint of handling various tray and card widths, wherein the adjusting of the machine to handle another width requires manipulation of several controls on the machine, and in some cases, the substitution of larger or smaller parts. Still further difficulty has been encountered in tightly wrapping the package and sealing the flaps to the bottom thereof.

Accordingly, it is an object of this invention to provide a new and novel machine for wrapping and pre-packaging trays and cards having food supported thereon, wherein a tightly wrapped, neat, heat-sealed package is obtained.

A further object of this invention is in the provision of a wrapping machine for automatically folding and sealing the flaps of a package to produce a tightly wrapped and sealed package.

Still a further object of this invention resides in the provision of a wrapping machine having a single control to effect adjustment accommodating various widths of trays and cards of a given height, and in accommodating trays of various heights.

Another object of this invention is to provide an efficient wrapping machine having a small number of reciprocating members which speeds up the overall wrapping operation and enables a greater number of packages to be wrapped within a given period of time.

Still another object of this invention is in the provision of a folding and tucking unit capable of permitting straight through operation, wherein the folding and tucking steps are effected while the package is moving.

Still another object of this invention resides in the provision of an improved side sealing unit, wherein the wrapping material is stretched tightly over the package during the side sealing operation, and a portion of the side flaps are heat-sealed to the bottom of the package.

A further object of this invention is to provide means ahead of the folding and tucking unit for urging downward the side flaps as they move into the mouth of the overlapping folding plates, which means is especially effective on high packages.

A further object consists in the provision of a new and improved method for tucking and folding the side flaps of a package while the package is in motion, and in stretching the wrapping material over the package during the side sealing operation.

Other objects, features, and advantages of the invention will be apparent from the following detailed disclosure, taken in conjunction with the accompanying sheets of drawings, wherein like reference numerals refer to like parts, in which:

Fig. 1 is a perspective view looking down on the machine and in the direction of movement of the conveyers;

Fig. 2 is a partially broken and fragmentary top plan view of the wrapping machine according to the invention, with some parts removed for purposes of clarity;

Fig. 3 is a partially broken side elevational view of the wrapping machine of the invention showing some parts in section and other parts in elevation;

Fig. 4 is a more or less diagrammatic view of the

operating components of the machine with the housing and other parts removed;

Fig. 5 is a top plan view of one side of the folding and tucking unit, with some parts omitted, and looking generally along line 5—5 of Fig. 3 and in the direction of the arrows;

Fig. 6 is a transverse sectional view, taken substantially along line 6—6 of Fig. 3;

Fig. 7 is a transverse sectional view, with some parts in elevation, taken along line 7—7 of Fig. 3;

Fig. 8 is a transverse sectional view, with some parts in elevation and illustrating the package in phantom, and taken substantially along line 8—8 of Fig. 3;

Fig. 9 is a view similar to Fig. 8 with the movable parts in a different position;

Fig. 26 is a perspective view of the hold-down device mounted over the heat-sealer bar adjacent the discharge end of the machine.

The machine in general

The particular construction herein illustrated, for the purpose of illustrating the wrapping machine of the present invention, is shown in wrapping a tray or pan loaded with food, but the wrapping of cards or boards with food thereon is also included. The machine of the present invention includes generally a delivery table 10 upon which the partially wrapped package is initially arranged, a folding and tucking unit 11 for folding the side flaps down and tucking the flaps, a side sealing unit 12 for tightly sealing the wrapping material about the package, a bottom folding and sealing unit 13 for folding and sealing the flaps tightly over the bottom of the package, and a receiving table 14 for receiving the completely wrapped package, Figs. 1, 2, and 3. A package such as that shown in Fig. 11 is advanced along the delivery table and through the tucking and folding unit 11 which tucks the side flaps and folds them downwardly, Fig. 21. The packages are then moved to the side sealing unit 12 for sealing the folds of the flaps together and a portion of the flaps to the opposite sides of the package, Fig. 23. The package is then conveyed to the bottom folding and sealing unit 13 and to the delivery table 14 for subsequent distribution.

The various operational units of the machine are generally supported on a central cabinet structure also serving as a supporting structure and having opposite side walls 15 and 16, and front and back walls 17 and 18, respectively, all suitably connected together and reinforced to define a rigid and durable framework for the machine, as well as enclosing several moving parts thereof. It may be noted that the receiving table 10 is suitably secured to the front wall 17 while the delivery table 14 is removably secured to the rear wall 18 and at a lower level thereof. In order to enhance the movability of the entire machine so that it may be easily moved along a floor from one place to another place, it is mounted on a plurality of casters 19, Figs. 1 and 3. The packages are advanced from the receiving table 10 and through the machine to the delivery table 14 by a first conveyer 20 and a second conveyer 21. The first conveyer advances the packages from the receiving table 10 and on through the tucking and folding unit 11 and deposits the package in the side sealing unit 12, while the second conveyer advances the package from the side sealing unit through the bottom folding and sealing unit 13 and to the receiving table 14.

The first conveyer includes a pair of endless members 22 having aligned pushing lugs 23 mounted thereon which engage the trailing end of the package as seen in Fig. 1. These endless members may be chains, such as illustrated, or any other suitable type of endless member, and are trained around longitudinally spaced rotatable wheels or sprockets 24 and 25, Figs. 3, 4, and 7. The sprockets 24 are rotatably carried on a shaft 26 horizontally disposed at the head end of the delivery table 10, while the sprockets 25 are carried on a shaft 27 positioned at the rear end of the folding and tucking unit 11 and the front end of the side sealing unit 12.

The head shaft 26 is rotatably mounted in bearings 28, Fig. 3 which are carried on an adjustable tensioning device 29 controlled by knobs 30, Figs. 1 and 3 for properly tensioning the endless members 22. The tensioning device will be mounted on a stationary part of the framework enclosed within the receiving table housing. Similarly, the shaft 27 is rotatably carried in bearing members 31, Fig. 7, mounted on a stationary portion of the framework within the main cabinet housing. The conveyer 20 advances the packages along a supporting strip or table 32 which extends along the receiving table 10 and through the folding and tucking unit 11, and is suitably supported by the stationary framework of the machine.

20 Fig. 11 is a detailed sectional view, taken substantially along line 11—11 of Fig. 8;

25 Figs. 12 through 25, inclusive, are perspective views illustrating the operational steps accomplished by the machine of the present invention during the tucking, folding, and heat-sealing of the side flaps to the package; and

30 Fig. 26 is a perspective view of the hold-down device mounted over the heat-sealer bar adjacent the discharge end of the machine.

In order to drive the conveyer 20, a sprocket or pulley 34 is mounted on the rear shaft 27 to co-rotate therewith, and engages an endless member 35, such as a chain or belt which is also trained around a sprocket or pulley 36 carried on a main drive shaft 37, Fig. 4, which extends transversely of the machine and is suitably supported between the side walls 15 and 16.

Also mounted on the main drive shaft 37 is a gear wheel 38 which meshes with a smaller pinion gear 39 on a second intermediate shaft 40, Figs. 3 and 4. This second shaft 40 is also suitably mounted between the opposite side walls 15 and 16 of the main cabinet housing. The shaft 40 carries a pulley 41 connected to a motor pulley 42 through a suitable endless belt 43. The motor pulley 42 is carried on a motor shaft 44 of a motor 45. The motor 45 is supported on a base 46, Fig. 3, pivoted at one end at 47 to the frame of the main cabinet housing. The weight of the motor 45 swings the motor around the pivot 47 and maintains the proper tension on the belt 43. It will be noted that the sizes of the pulleys 41 and 42, and the gears 38 and 39 are such as to effect a speed reduction between the motor shaft 44 and the main drive shaft 37. The motor 45 constitutes the sole power source for moving all of the movable parts of the machine; and all of the movable parts are operated from the main drive shaft 37 in synchronism.

Referring to Fig. 12, a tray 48 is shown with a sheet of wrapping material 49 arranged therearound. The trays are generally of a relatively stiff paper, such as cardboard, with upwardly sloping sides and a peripheral flange at the upper open end, while the wrapping material may be of any thermoplastic material, such as transparent cellophane or Pliofilm, but preferably cellophane. The present invention is illustrated in use for forming the "diamond wrap," but it will be understood that it may also be employed to form the "square wrap." In initially fashioning the diamond wrap, the sheet of wrapping material 49 is manually arranged around the tray 48, so that the diagonal corners of the sheet are in overlapping relationship on the bottom of the tray and the sheet forms a tube around the tray with oppositely extending side flaps 50 extending from opposite sides of the tray. The tray with the wrapping material arranged therearound is then passed over a heated seal

ing bar 51 mounted at the head of the delivery table 10, Fig. 1, to tack-seal the overlapping diagonal corner portions together on the bottom of the tray, this step being illustrated by Fig. 13. As seen in Figs. 1, 2, and 3, the sealer bar 51 is mounted at the infeed side of the receiving table 10 and the conveyer 20 and at an elevated position above the conveyer bed by the casing 52. This is obviously a very convenient position to mount the sealer bar for quick access to the wrapping machine, and enables the tray with the material to be arranged there-around to be slipped directly onto the conveyer 20. As seen in Fig. 1, the package is arranged so that the longitudinal axes of the side or end flaps 50 of the package extend transversely of the machine and the direction of movement of the conveyer 20. Further, it will be noted that the opposite side walls of the tray 48 are positioned between the guide rails 33 so that the package may be guidedly advanced along the supporting strip 32 to assure proper positioning of the tray and side flaps when they enter the folding and tucking unit 11.

The folding and tucking unit

The wrapping of a normal height tray generally presents fewer problems in effecting a proper heat sealed package, and will be described herein in detail. But where a tray is filled and stacked relatively high with food, such as freshly ground meat or poultry, as indicated at 53 in Fig. 14, it is difficult to maintain the side flaps in a position close to the bottom of the tray so that they may be properly received in the folding and tucking unit 11. In machines heretofore developed, it has been virtually impossible to wrap a tall package, such as that illustrated in Figs. 14 and 15 since the side flaps could not be properly fed to the holding and tucking unit. This problem is overcome by the present invention, wherein a pair of transversely spaced power driven gathering rollers 54, Figs. 1, 2, 3, and 5 are mounted in superposed position above the conveyer 20 and immediately ahead of the folding and tucking unit 11. These rollers are coaxially mounted and spaced from one another so as to engage the upper side of the cellophane wrapper at the inner end of the side flaps 50 as seen in Fig. 14.

The gathering rollers 54 are preferably constructed of a resilient material, such as rubber to cushion the effective contact with the cellophane and prevent tearing thereof as well as to generate a frictional contact with the cellophane. The linear speed at the periphery of the gathering rollers 54 is greater than the linear speed of the conveyer 20 thereby assuring that no drag is transmitted to the package against the action of the conveyer pushing lugs 23 which would disrupt the wrapping process, and possibly tear the cellophane.

Each gathering roller 54 is mounted on a stub shaft 55 which is journalled in the outer free end of a swingable supporting arm 56, Fig. 5. The other end of the supporting arm is pivotally carried on a shaft 57 spaced rearwardly and parallel to the stub shaft 55 and cantileverly carried in a bearing bracket 58. The bearing bracket 58 is rigidly secured to the inner face of a vertical frame member 59 of the tucking and folding unit 11, Figs. 5 and 6. The roller supporting arms 56 are angularly related to the longitudinal axis of the machine, Figs. 2 and 5, and rest intermediately on a stop 60, Fig. 3, suitably connected to the frame of the unit to limit the downward movement of the roller while allowing the roller to swing around the shaft 57 in an upward direction should the height of the package so demand.

Driving of each roller 54 is accomplished through a chain and sprocket arrangement including a sprocket 61, Figs. 3, 4, and 5 mounted on the roller shaft 55 and driven by a sprocket 62 carried on the shaft 57 through an endless chain 63. A second sprocket 64 is also mounted on the shaft 57 coaxial with the sprocket 62

and drivingly connected to a rearwardly spaced sprocket 65 carried on a stub shaft 66 by an endless chain 67, Figs. 3, 4, 5, and 6. The stub shaft 66 is journalled in a bearing bracket 68, Fig. 5, which is supported on an inwardly turned portion of the vertical frame member 59 by welding or other suitable means. A miter or bevel gear 69 is carried on the inner end of the stub shaft 66 and in meshing engagement with a second miter or bevel gear 70 displaced 90° from the first miter gear and carried on the vertical shaft 71, Figs. 4, 5, and 7. The opposite ends of the shaft 71 are suitably journalled in parallel spaced upper and lower frame members 72 and 73, Figs. 6 and 7, which extend inwardly from the top and bottom edges of the vertical frame member 59. The shaft 71 carries a sprocket 74 which is driven by a sprocket 75 through an endless chain 76. The sprocket 75 is carried on a vertical shaft 77 spaced rearwardly from the shaft 71, Figs. 3, 4, and 5, and rotatably supported by bearing brackets 78, 79, and 80, Fig. 3. The bearing bracket 78 is integral with the upper frame member 72, and the bearing bracket 79 is suitably secured to the inwardly turned portion of the vertical frame member 59, Fig. 5.

After the leading edges of the package flaps 50 travel beyond the gathering rollers 54, each contacts a downwardly sloping guide 81 which is integrally connected to an upper folding plate 82. This plate 82 is secured along its top edge to the inner end of the frame member 72, Fig. 6. The action of the guide 81 is illustrated in Fig. 16. While this guide is integrally connected with the upper folding plate 82, it may be a separate bar if desired.

Each upper folding plate 82 coacts with a lower folding plate 83 attached at its bottom edge to the inner end of the lower frame member 73, Fig. 6, and extending upwardly with its upper edge overlapping the lower edge of the upper folding plate 82 and on the inside face thereof but in slightly spaced relationship therewith. At the forward end of each lower folding plate, a front tucker 84 is sloped upwardly from front to rear, Fig. 3, terminating at a point ahead of the point where the upper edge of the lower folding plate crosses the downwardly sloping guide 81 of the upper folding plate, and serves to tuck the leading edge portions of the package flaps 50.

Before the leading edge portions of the side flaps 50 are engaged by the front tucker 84, they are contacted by upper and lower rear tucker rollers 85 and 86, respectively, which coact to tuck the trailing portions of the flaps 50 and initiate the downward folding of these flaps. These rollers are preferably made of a resilient material, such as rubber and are provided with generally frusto-conical flap engaging faces arranged to turn down the flaps. With respect to a set of rollers at one side, each upper rear tucker roller 85 is carried on the shaft 57, Figs. 5 and 6, for co-rotation therewith and to be driven by this power driven shaft. As seen in Fig. 6 it will be noted that when the upper and lower rollers 85 and 86 are in coacting position, the peripheral edge along the larger diameter of the lower roller is substantially aligned on a horizontal plane with respect to the upper edge of the lower folding plates 83 and accordingly aligned with the side flaps 50. The upper horizontal edge of each lower folding plate 83 is also substantially in line with the bottom edge of the flange on the tray 48.

Each lower rear tucking roller 86 is rotatably carried on a pin 87 mounted to an arm 88 of a bell crank 89, Fig. 3. The arm 88 normally extends horizontally, while the arm 90 normally extends vertically and the bell crank is pivotally mounted at 91 to the free end of a bracket support 92 which is secured to the upstanding vertical frame member 59, Fig. 5. Thus, it will be seen that oscillation of the bell cranks 89 move the lower rear tucking rollers 86 into and out of coaction with the upper rear tucking rollers 85.

Thus, the upper roller 85, which is power driven, drives the lower roller 86. It may be appreciated that the flaps

move in the same direction as the rollers; and therefore, to tuck the trailing portions of each flap, it is necessary to drive the rollers at a speed greater than the speed of the conveyor. In order to obtain the best possible tucking action, it is also desirable to slip the material at the underside of the flaps under faster. To accomplish this action, the upper rollers 85 are beveled at 85a, this also relieving the upper part of the flaps from being gripped at the inner portions nearest the package. Further, the upper rollers being larger effects driving of the lower rollers at a higher speed. Hence, the inner parts of the lower rollers which are not engaged by the upper roller effects faster slipping under of the material of the flaps.

In order to impart oscillation to the bell cranks 89, the outer end of each arm 90 is pivotally secured to one end of an intermediate link 93 at 94. The other end of the links slidably pivot on a cross rod 96, Figs. 3, and 6. The slideable pivot is necessary in order to compensate for vertical adjustment of the folding and tucking unit 11 as will be hereinafter more clearly described. The crossrod 96 is pivotally supported at opposite ends by links 95 and 95a, Fig. 6, which are, in turn, pivoted to a cross shaft 99 mounted at opposite ends in bearings 100, 100 secured to the front wall 17. The link 95 carries an extension which is connected to a cam follower 97 by a pivot 98. The cam follower 97 is in the form of an elongated bar with the end opposite the end connected at 98 to the bar 95 being bifurcated and slidably received on the drive shaft 37. Between the ends of the cam follower 97 is a roller 101 which is received by a cam track 102a of a cam wheel 102 secured to and rotatable with the drive shaft 37, Fig. 4. The cam track is arranged so that the bite between the upper and lower rear tucker rollers opens to receive the leading edge portions of the flaps 50 and to close shortly after the flaps have entered between the bite thereof. Therefore, it is seen that the movement of the lower rear tucker rollers 86 is timed with the movement of the infeed conveyer 20, and particularly with the positioning of the lugs 23 on the conveyor chains. In Fig. 18, the movement of the tucker rollers 86 is expressed by the arrows 103, wherein the rollers move from the dotted line position to the solid line position for engaging the flaps 50 of the package.

The subsequent coaction between the downwardly sloping guide 81 on the upper plates 82 and the horizontal upper edge 104, Fig. 20, of each lower folding plate 83 serves to aid in gradually folding the flaps 50 of the package downwardly until the flaps take a substantially vertical position with respect to the package as seen in Fig. 19.

Because the overlapping folding plates will effect a friction drag on the side flaps of the package which will cause the flaps to lag behind the movement of the package as the conveyer advances the package through the tucking unit, means are provided to advance the lower ends of the flaps at a speed faster than the movement of the package. This means includes a power driven auxiliary feed roll 105, Fig. 7, rotatable about a vertical axis at opposite sides of the tucking plates to coat with the lower tucking plates 83 and engage the side flaps therebetween. Preferably, these auxiliary feed rollers are made of rubber in order to increase their frictional contact with the side flaps and to compensate for various thicknesses of packaging materials. These auxiliary feed rolls are also driven at a higher speed than the conveyor 21 in order to compensate for the lag of the flaps caused by the frictional contact with the tucking plate and to slightly advance the flaps ahead of the package as they leave the tucking unit. As seen most clearly in Fig. 7, the auxiliary feed rolls 105 are mounted on the vertical power driven shafts 71 and are arranged below the lower edges of the upper folding plates 82. These side flaps of the package are thereby properly arranged with respect to the package when the package is delivered from the tucking unit 11 into the side sealing unit 12 whereby the

flaps may then be properly folded underneath the bottom of the package and sealed thereto.

Each side of the tucking unit is mounted on a longitudinally extending angle bar 106, Figs. 6 and 7, which has downwardly extending lugs 107 mounting rigidly thereon nuts 108. These nuts 108 are threadedly received on a transversely extending and adjusting rod 109 having threading of one hand at 110 and threading of the other hand at 111, Fig. 7. The rod 109 is suitably journaled in bearings carried by the opposite end walls 15 and 16, and the rod extends outwardly beyond one of the end walls to receive a crank handle 112. This arrangement is provided since it is desirable that the wrapping machine of this invention be adaptable to handle many different sized trays or pans for wrapping materials therein.

A vertically extending tubular support 113 is slidably received on a cylindrical bar 114 in each side of the tucking unit. The lower end of each tubular support is rigidly secured to a corresponding angle bar by a bracket 115, while the upper end carries a nut 116 thereon which receives a threaded screw member 117. Each screw member is mounted in the upper frame member 72 for rotation therewith, but arranged to preclude axial movement therewith, and carries a knurled knob 118 at the outside of the frame member. As seen in Fig. 2, a second transversely extending rod 119 is mounted at the opposite side walls, and is drivingly connected to the first rod 109 by means of an endless member, such as a chain 120 trained over a sprocket 121 on the rod 109 and a sprocket 122 on the rod 119. Although not shown, the rod 119 is also threaded to coat with nuts connected to the angle bars 106 by means of lugs.

Accordingly, rotation of the crank 112 imparts movement to the nuts 108, the lugs 107 and the angle bars 106 in opposite directions to either move the opposed tucking components toward each other or away from each other depending upon the width of the pan or tray desired to be wrapped. The guide rails 33 are also secured to the angle bars 106 and accordingly are adjusted during a width adjustment. This action takes place because of the opposite threads on the rods 109 and 119. It will be noted that the conveyer chains 22 and the supporting strip or table 32 remain stationary during adjustment of the opposing tucking components, and that it is not necessary that these latter elements be adjustable in any manner in order to effect width adjustment for the tucking unit. Because of the slideable connection between links 93 and the shaft 96, Figs. 3 and 6, it will be seen that the bell crank 89 and its associated linkages with respect to the lower movable tucking rollers 86 will slide along the shaft 96 when adjustments are made by the operation of the rods 109 and 119.

Since it is also desirable that the wrapping machine of the present invention be adaptable to handle pans and trays of different heights for wrapping thereof, it is therefore necessary to provide an adjustment whereby the components of the tucking unit may be raised or lowered relative to the stationary supporting table 32 and the conveyer elements or chains 22. Accordingly, the entire group of tucking components on each side may be raised or lowered by manipulation of the threaded screw members 117 as operated by the knobs 118. Rotation of the screw members 117 in one direction causes the vertical frame members 59 and the upper frame members 72 and the lower frame members 73, all of which mount the various tucking components, to be elevated, whereby the bar 114 slides within the tubular supports 113 held on the angle bars 106. Rotation of the screw members 117 in opposite directions causes all of the frame members to be lowered with the tucking components in order to take a tray or pan of lesser depth. Generally, the lip around the pan will be positioned so that it rides over the top edge of the lower folding plates 83, and the bottom of the pan will then ride on the supporting table 32. So as the depth of the tray becomes greater, it is necessary

to readjust the tucking components so that the upper edge of the lower folding plates 83 is raised relatively above the supporting table 22.

Side sealing unit

The lugs 23 on the conveyer 22 will effect feeding of the package from the tucking unit 11 into the side sealing unit 12. In the side sealing unit 12, the package is received on and supported by the upper longitudinal edges of spaced inner gripping elements 123, Figs. 9 and 21. The now tucked flaps 50, extending substantially in a vertical direction enter between the inner gripping elements 123 and outer gripping elements or heating shoes 124. These heating shoes will be generally energized and heated to a temperature suitable for heat sealing the cellophane in the final wrapping steps. After the package has been received as seen in Figs. 8 and 20 in the side sealing unit 12, the heating shoes move inwardly and upwardly along an arcuate path, coming in slightly below the package bottom and then lifting the package to raise it from the inner gripping elements and thereby assure that the package bottom rests on the top of the hot heating shoes 124 to effect a better seal and to seal that portion of the cellophane to the bottom of the package. As the heating shoe is moved inwardly, the side flaps 50 of the package are folded until they approximate the contour shown in Figs. 10 and 23, wherein a portion of the flaps has been bent inwardly and against the bottom of the package and another portion of the flaps remains in a substantially vertical position. After the shoes engage the bottom of the package they completely support the package until it is moved from the shoes by the second conveyer 21. But before the package is moved from the shoes, the inner gripping elements 123 are moved slightly inwardly in order to release the grip on the side flaps with respect to the outer gripping elements or heating shoes 124.

The inner gripping elements are pivotally mounted at their lower ends to horizontally extending bars 25 which are, in turn, rigidly secured to the longitudinally extending angle bars 106 by upstanding plates 126. Actually, a pair of bars 125 are arranged at the opposed positions in longitudinally spaced and transversely spaced relation, and the inner gripping elements 123 are pivotally carried at the inner ends of the bars 125 at 127. The inner gripping elements 123 are normally biased outwardly by springs 128 against stops 129. The stops 129 are adjustably fastened to the upstanding plates 126, while one end of each spring 128 is connected to the plates 126 and the other end to the inner gripping elements 123.

The inward and upward arcuate movement of the shoes 124 is accomplished by a parallelogram linkage arrangement which includes an upper bar 130 having the shoes connected to the inner ends thereof and being pivotally connected to parallel links 131 and 132. The parallel links 131 and 132 are also similarly pivotally connected to the lower stationary bars 125. Specifically, each inner link 131 is pivoted at its upper end to the horizontally extending upper bar 130 at 133 and secured to a longitudinally extending shaft 134 pivotally carried in the lower stationary bars 125.

Similarly, the links 32 are pivotally connected at their upper ends to the horizontal bar 120 by a longitudinally extending shaft 135, while the lower ends are pivotally connected to the lower bars 125 at 135a.

The parallelogram linkages are operated by actuating levers 136 rigidly secured at one end to the shaft 134 and pivotally mounted at the other end to blocks 137, Figs. 8, 9, and 11, which are slidably received on a square cross bar 138. This cross bar 138 is oscillated up and down by a cam wheel 139 mounted on the drive shaft 37, Fig. 4, through a bell crank 139a, a bar 139b and a cam actuated lever 140. The bell crank 139a and the bar 139b are carried on a shaft 141 mounted on the frame of the machine. The bell crank 139a is pivoted

at one end to the cross bar 138 and at the other end to the lever 140 while the bar 139b is pivoted at one end to the bar 138. A cam follower 142 is carried on the cam lever 140 and coacts with a cam track 143 formed in the cam wheel 139. The end of the cam lever 140 opposite its pivotal connection to the bell crank 139 is bifurcated for slidable relation over the drive shaft 37 which thereby permits only substantially reciprocating movement of the cam lever 140. Inasmuch as the cam lever 140 which operates the cam linkages of the side sealing unit, is operated from the drive shaft 37 which also operates the tucking rollers 86 in the tucking unit, these elements are arranged in timed relation to act synchronously with each other. Further, the tucking unit and side sealing unit are arranged in timed relationship with respect to the conveyer 20 which is also driven from the drive shaft 37.

Since it is desirable to effect a tight wrapping of the cellophane around the package, the heating shoes 124 and the inner gripping elements 123 initially grip the side flaps 50 of the package a slight distance under the bottom of the package, as seen most clearly in Fig. 21, and then pull the side flaps tightly underneath the package until the heating shoes 124 have lifted the package above the inner gripping elements 123, as seen more clearly in Fig. 9. By virtue of the early gripping action effected by the heating shoes 124 and the inner gripping elements 123, the cellophane will be pulled taut around the package and sealed thereto. The action takes place with respect to the side flaps as soon as the heating shoes 124 begin to apply pressure against the flaps in coaction with the inner gripping elements 123. The inner gripping elements are pivoted inwardly to an inward position as seen in Fig. 10 by the movement of the heating shoes 124. Normally, the inner gripping elements 123 will assume a position such as that shown in Fig. 9, and will then move inwardly against the force of the springs 128. This force may be adjusted by utilization of different size springs 128. When the heating shoes 124 have reached the properly desired inward position and perform the desired sealing and tightening operations on the package, wherein the upper portions of the side flaps are then sealed to the bottom of the package, further inward movement of the heating shoes effects a releasing of the gripping action by a faster inward movement of the inner gripping elements 123. This is accomplished by adjustable cam followers 144 carried by the links 131 of the parallelogram linkage, Figs. 8 and 9, which are spaced above the shafts 134 or lower pivot points of the links 131, and engage cam plates 144a secured to the gripping elements 123. As the rollers travel over the inclined cam surface of the cam plates, a fast inward movement of the gripping elements is obtained. Since the rollers 144 follow a path along an arc having a radius extending from the shaft 134 to the outer end of the pin, the latter of which engages the cam plates on the inner gripping elements 123, and the heating shoes move along an arcuate path about the shaft 134 which also has an upward component because of the parallelogram linkage, the rollers will therefore move faster along the arcuate path so that further inward movement of the shoes 124 after they reach a certain point causes the inner gripping elements to be moved away quickly from the heating shoes and thereby release the gripping action on the side flaps 50 of the package.

Since it is also necessary that the side sealing unit be adjusted for varying widths of pans adapted to be wrapped in the machine, and since it has already been explained that the opposing heating shoes and components are mounted on the transversely spaced angle bars 106, adjustment of the machine for a different width of pan or tray will effect simultaneous adjustment in the side sealing unit. And for this reason, the blocks 137 are slidably associated with the cross bar 138 and will

therefore slide thereon during movement of the elements inward or outward.

Bottom folding and sealing unit

Upon release of the package side flaps 50 in the side sealing unit 12, lugs 145, Figs. 2 and 4, preferably of a resilient or rubber material, are brought to bear behind the package and to carry or advance the package from the side sealing unit. These lugs 145 are mounted on endless carrying members or chains 146 of the conveyer 21, these chains being trained around longitudinally spaced sprockets 147 and 148, Figs. 2 and 4, which are arranged to support the runs of the chains 146 in a horizontal plane, as seen in Fig. 2. The forward sprockets 147 are carried on the vertical shaft 77, Fig. 3, mounted in association with the tucking unit 11, while the rear sprockets 148 are mounted on vertical shafts 149. The vertical shafts 149 are carried in bearing supports 150, Fig. 3, which are rigidly secured to the spaced angle bars 106, and accordingly moved therewith on adjustment of the machine for handling various widths of pans or trays. Both vertical shafts 149 are drivingly connected to a transversely extending horizontal shaft 151, Figs. 2 and 4, which is bearingly supported at opposite ends in the opposite end walls 15 and 16 of the machine. Elements drivingly connecting shafts 149 and 151 includes a sprocket 152 on each vertical shaft 149 and an endless drive member or chain 153 trained over the sprocket 152 and a sprocket 154 mounted on a vertical shaft 155, Fig. 4. Each vertical shaft 155 is suitably supported in a bearing bracket 156, Fig. 3. A miter gear 157 is carried on the shaft 155 and in meshing engagement with a miter gear 158 carried on the cross shaft 151. The miter gear 158 on the shaft 151 is arranged so that it will co-rotate with the shaft 151, but may be slidably moved therealong during the adjustment of the machine. Accordingly, shaft 151 may be splined. To further support the miter gear 158 and assure its meshing engagement with the miter gear 157 and proper movement along the shaft 151, a bracket 159 is attached thereto and to each angle bar 106, Fig. 2.

As seen in Fig. 4, the shaft 151 is drivingly connected to the power shaft 37 by means of a sprocket 160 mounted on the shaft 151, a sprocket 161 carried on the power shaft 37, and an endless transmission member such as a chain 162 trained over said sprockets. A chain tightening pulley 163 is suitably carried by the machine frame for adjusting the tension in the chain 162. Since the conveyer 21 is also driven from the main power shaft 37, it is synchronized in timed relationship with the first conveyer, the tucking unit and the side sealing unit so that all of the operations are performed in synchronized relationship.

The lugs 145 on the conveyer 21 push the package along the transversely spaced supporting bars 164, Fig. 2, mounted on upstanding standards 165 which are carried on the angle bars 106. Accordingly the spacing of the supporting bars 164 varies in accordance with the spacing in the tucking and side sealing units when width adjustments are made to the machine. As seen most clearly in Fig. 2, the supports are spaced apart at least a distance so that the flaps 50 are freely received therebetween.

The flaps on the package are further folded inwardly to the bottom of the package by a bottom folding plate 166 having a V-shaped side 167 facing the side sealing unit 12. The package approaches the V-shaped side 167 of the plate 166 in the manner shown in Fig. 24. The flaps are gradually folded inwardly under the bottom of the package. The conveyer 21 continues to advance the package from the machine and over a heated sealing plate or bar 168, Figs. 2 and 25, where the flaps are sealed to the bottom of the package, and discharges the package into a receptacle or the like which may be supported on the delivery table 14.

Some of the packages wrapped are relatively light in

weight, and therefore, the sealing of the flaps to the bottom of these packages as they are conveyed across the heating plate 168 may be unsatisfactory. To alleviate this possible condition, hold down or presser bars 170 are mounted at opposite sides of the machine above and in the vicinity of the sealing plate 168, as seen in Figs. 1, 3, 25, and 26. These bars engage along the opposite upper edges of the packages and bias same against the heating plate to assure proper sealing action. The bars 170 are mounted on the chain guide plates 171 of the conveyer 21 by a parallelogram linkage arrangement. This linkage arrangement includes links 172 and 173 pivotally connected at each end of the bars and also connected to shafts 174 and 175, respectively. Each shaft 174 and 175 is respectively journaled in bearing supports 176 and 177 connected together by an elongated bar 177a. Brackets 178 and 179 extend from the bearing supports 176 and 177, respectively and are provided with slots 180 and 181, respectively. The axes of the slots are normal to the hold down bars and provide means for adjusting the bars transverse the machine if desired, although the bars would move in and out with the width adjustment of the machine. The slots receive threaded studs 182 and 183 respectively which are carried by upstanding supports 184 and 185 secured to the guide plates 171. Knurled nuts 186 and 187 are received by the studs 182 and 183, respectively, for locking the brackets and hold down bars in adjusted position. A weight bar 188 is connected to the outer end of each shaft 174 and adjustably carries thereon a weight 189. This weight, adjustable along the weight bar, transmits weight to the hold down bar 170 through the weight bar 188, the shaft 174, and the link 172. In order to prevent the hold down bar from striking the heating plate when no package is traveling thereacross, an adjustable stop 190 is carried by the weight bar 188 and arranged to engage the chain guide plate 171.

Preferably, the temperatures of the heating bar 51, the sealing shoes 124, and the sealing plate 166 are thermostatically controlled by adjustable thermostats, not shown, which may be mounted on the end walls of the machine frame, or any other suitable place.

From the foregoing, it is seen that the wrapping machine of the present invention performs certain wrapping operations on a package while the package is conveyed straight through the machine, and including the tucking and sealing operations, thereby providing a package which is tightly wrapped and sealed and having an excellent appearance for the public eye.

It will be understood that modifications and variations may be effected without departing from the scope of the novel concepts of the present invention, but it is understood that this application is to be limited only by the scope of the appended claims.

The invention is hereby claimed as follows:

1. In a wrapping machine adapted to receive and complete the wrapping of an article that is partially wrapped by a sheet of transparent heat-sealable material wherein side flaps extend laterally from opposite sides thereof, a horizontally extending support, longitudinally extending and transversely spaced guide bars along part of said support, conveyer means for continuously advancing the article along said support and between said guide bars, a folding and tucking unit along said support adapted to fold and tuck said side flaps, said unit comprising a front tucker tucking the leading edge portions of the flaps, said front tucker including a pair of transversely spaced upwardly sloping members, a rear tucker tucking the trailing edge portions of the flaps, said rear tucker including a pair of coating rollers, the linear speed of said rollers at the outer periphery thereof being greater than the linear speed of said conveyer, overlapping vertical plates folding the flaps downwardly along the sides of the package, whereby the flaps are tucked and folded in one continuous operation as they are advanced continuously along the support.

2. In a wrapping machine adapted to receive and complete the wrapping of an article that is partially wrapped by a sheet of transparent heat-sealable material wherein side flaps extend laterally from opposite sides thereof, a horizontally extending article support, longitudinally extending and transversely spaced guide bars along part of said support, conveyer means for continuously advancing the article along said support and between said guide bars, the axes of said flaps extending transverse to the direction of conveyer travel, a folding and tucking unit along said support adapted to fold and tuck the side flaps, said unit comprising a first tucker for leading edge portions of said flaps, said first tucker including a pair of transversely spaced upwardly sloping members, a second tucker for tucking the trailing edges of the side flaps, said second tucker including transversely spaced pairs of coacting rollers, one of said rollers of each pair being power driven, the linear speed of said rollers at the outer periphery thereof being greater than the linear speed of said conveyer, overlapping vertical plates folding the flaps downwardly along the sides of the package, whereby the flaps are tucked and folded in one continuous operation as they are advanced continuously along the support.

3. In a wrapping machine adapted to receive and complete the wrapping of an article that is partially wrapped by a sheet of transparent heat-sealable material wherein side flaps extend laterally from opposite sides thereof, a horizontally extending article support, longitudinally extending and transversely spaced guide bars along part of said support, conveyer means for continuously advancing the article along said support and between said guide bars, the axes of said flaps extending transverse to the direction of conveyer travel, a folding and tucking unit along said support adapted to fold and tuck the side flaps, said unit comprising a first tucker for tucking the leading edge portions of said flaps, said first tucker including a pair of transversely spaced upwardly sloping members, a second tucker for tucking the trailing edges of the side flaps, said second tucker including transversely spaced pairs of coacting rollers, one of said rollers of each pair being power driven, the linear speed of said rollers at the outer periphery thereof being greater than the linear speed of said conveyer, the other roller of each pair being movable toward and away from said one roller in time sequence to permit the leading edge portions of the side flaps to be easily gripped thereby, and overlapping vertical plates folding the flaps downwardly along the sides of the package, whereby the flaps are tucked and folded in one continuous operation as they are advanced continuously along the support.

4. In a wrapping machine adapted to receive and complete the wrapping of an article that is partially wrapped by a sheet of transparent heat-sealable material wherein side flaps extend laterally from opposite sides thereof, a horizontally extending article support, longitudinally extending and transversely spaced guide bars along part of said support, conveyer means for continuously advancing the article along said support and between said guide bars, the axes of said flaps extending transverse to the direction of conveyer travel, a folding and tucking unit along said support adapted to fold and tuck the side flaps, said unit comprising a first tucker for tucking the leading edge portions of said flaps, said first tucker including a pair of transversely spaced upwardly sloping members, a second tucker for tucking the trailing edges of the side flaps, said second tucker including transversely spaced pairs of coacting rollers, one of said rollers of each pair being power driven, the linear speed of said rollers at the outer periphery thereof being greater than the linear speed of said conveyer, the other roller of each pair being movable toward and away from said one roller in time sequence to permit the leading edge portions of the side flaps to be easily gripped thereby, each pair of rollers having generally frusto-conical engaging faces

and arranged to bend down the side flaps along the article, overlapping vertical plates folding the flaps downwardly along the sides of the package, whereby the flaps are tucked and folded in one continuous operation as they are advanced continuously along the support.

5. In a wrapping machine adapted to receive and complete the wrapping of an article that is partially wrapped by a sheet of transparent heat-sealable material wherein side flaps extend laterally from opposite sides thereof, a horizontally extending article support, longitudinally extending and transversely spaced guide bars along part of said support, conveyer means for continuously advancing the article along said support and between said guide bars, the axes of said flaps extending transverse to the direction of conveyer travel, a folding and tucking unit along said support adapted to fold and tuck the side flaps, said unit comprising a pair of power driven transversely spaced gathering rollers suspended over said support for holding down the side flaps, the linear speed of said rollers at the outer periphery being greater than the speed of the conveyer, a pair of downwardly sloping members serving to gradually force the flaps down, a first tucker for tucking the leading edge portions of said flaps, said first tucker including a pair of transversely spaced upwardly sloping members, a second tucker for tucking the trailing edges of the side flaps, said second tucker including transversely spaced pairs of coacting rollers, one of said rollers of each pair being power driven, the linear speed of said rollers at the outer periphery thereof being greater than the linear speed of said conveyer, overlapping vertical plates folding the flaps downwardly along the sides of the package, whereby the flaps are tucked and folded in one continuous operation as they are advanced continuously along the support.

6. In a wrapping machine adapted to receive and complete the wrapping of an article that is partially wrapped by a sheet of transparent heat-sealable material wherein side flaps extend laterally from opposite sides thereof, a horizontally extending article support, longitudinally extending and transversely spaced guide bars along part of said support, conveyer means for continuously advancing the article along said support and between said guide bars, the axes of said flaps extending transverse to the direction of conveyer travel, a folding and tucking unit along said support adapted to fold and tuck the side flaps, said unit comprising a pair of power driven transversely spaced gathering rollers suspended over said support for holding down the side flaps, the linear speed of said rollers at the outer periphery being greater than the speed of the conveyer, said rollers being carried on arms which are pivotally mounted at one end and gravity actuated, a pair of downwardly sloping members serving to gradually force the flaps down, a first tucker for tucking the leading edge portions of said flaps, said first tucker including a pair of transversely spaced upwardly sloping members, a second tucker for tucking the trailing edges of the side flaps, said second tucker including transversely spaced pairs of coacting rollers, one of said rollers of each pair being power driven, the linear speed of said rollers at the outer periphery thereof being greater than the linear speed of said conveyer, overlapping vertical plates folding the flaps downwardly along the sides of the package, whereby the flaps are tucked and folded in one continuous operation as they are advanced continuously along the support.

7. In a wrapping machine adapted to receive and complete the wrapping of an article that is partially wrapped by a sheet of transparent heat-sealable material wherein side flaps extend laterally from opposite sides thereof, a horizontally extending article support, longitudinally extending and transversely spaced guide bars along part of said support, conveyer means for continuously advancing the article along said support and between said guide bars, the axes of said flaps extending transverse to the direc-

tion of conveyer travel, a folding and tucking unit along said support adapted to fold and tuck the side flaps, said unit comprising a first tucker for tucking the leading edge portions of said flaps, said first tucker including a pair of transversely spaced upwardly sloping members, a second tucker for tucking the trailing edges of the side flaps, said second tucker including transversely spaced pairs of coacting rollers, one of said rollers of each pair being power driven, the linear speed of said rollers at the outer periphery thereof being greater than the linear speed of said conveyor, overlapping vertical plates folding the flaps downwardly along the sides of the package, an auxiliary feed roller coacting with the lower folding plate to advance the lower ends of the flaps at a faster rate than the conveyer, whereby the flaps are tucked and folded in one continuous operation as they are advanced continuously along the support.

8. In a wrapping machine adapted to receive and complete the wrapping of a tray or card having edible substances thereon which is partially wrapped by a sheet of transparent heat-sealable material wherein side flaps extend laterally from opposite sides thereof, a horizontally extending support for receiving the partially wrapped item, conveyer means for continuously advancing the item along said support with the axes of the flaps extending transverse the direction of conveyer travel, a folding and tucking unit along said support adapted to fold and tuck the side flaps as they pass therethrough and a side sealing unit for sealing said side flaps and sealing a portion of the flaps to the bottom of the item, said side sealing unit including a pair of grippers, each gripper receiving a flap and having a pair of gripping elements, and means for holding said gripping elements apart to receive the flaps and to grip the flaps and force them under the item to stretch the material about the item and effect a tightly wrapped package.

9. In a wrapping machine adapted to receive and complete the wrapping of a tray or card having edible substances thereon which is partially wrapped by a sheet of transparent heat-sealable material wherein side flaps extend laterally from opposite sides thereof, a horizontally extending support for receiving the partially wrapped item, conveyer means for continuously advancing the item along said support with the axes of the flaps extending transverse the direction of conveyer travel, a folding and tucking unit along said support adapted to fold and tuck the side flaps as they pass therethrough and a side sealing unit for sealing said side flaps and sealing a portion of the flaps to the bottom of the item, said side sealing unit including a pair of grippers, each gripper receiving a flap and having a pair of gripping elements, one of said gripping elements being heated to seal the flaps, and means for holding said gripping elements apart to receive the flaps and to grip the flaps and force them under the item to stretch the material about the item and effect a tightly wrapped package.

10. In a wrapping machine adapted to receive and complete the wrapping of a tray or card having edible substances thereon which is partially wrapped by a sheet of transparent heat-sealable material wherein side flaps extend laterally from opposite sides thereof, a horizontally extending support for receiving the partially wrapped item, conveyer means for continuously advancing the item along said support with the axes of the flaps extending transverse the direction of conveyer travel, a folding and tucking unit along said support adapted to fold and tuck the side flaps as they pass therethrough, and a side sealing unit for sealing said side flaps and sealing a portion of the flaps to the bottom of the item, said side sealing unit including a pair of grippers, each gripper receiving a flap and having a pair of gripping elements, one of said gripping elements being heated to seal the flaps, and means for holding said gripping elements apart to receive the flaps and to grip the flaps and force them under the item to stretch the material about

the item and effect a tightly wrapped package, said means spreading the gripping elements apart after the flaps have been subjected to the stretching operation.

5 11. In a wrapping machine adapted to receive and complete the wrapping of a tray or card having edible substances thereon which is partially wrapped by a sheet of transparent heat-sealable material wherein side flaps extend from opposite sides thereof, a side sealing unit for sealing the side flaps and sealing a portion of said flaps to the bottom of the item, said side sealing unit including a pair of grippers, each gripper receiving a flap and having a pair of gripping elements, one of said gripping elements being heated to seal the flaps, and means for holding said gripping elements apart to receive the flaps and to grip the flaps and force them under the item to stretch the material about the item and effect a tightly wrapped package, said means spreading the gripping elements apart after the flaps have been subjected to the stretching operation.

10 12. A side sealing unit for a wrapping machine for sealing side flaps of a package and sealing a portion of the side flaps to the bottom of the package, said unit comprising a pair of movable grippers, each gripper having a heated and a non-heated gripper member, said grippers being movable by a parallelogram linkage so as to initially grip the flaps and seal same and then seal a portion of the flaps to the bottom of the package.

15 13. A wrapping machine comprising, a pair of transversely spaced tucking units having means for folding and tucking side flaps of a package, a pair of side sealing units having means for stretching the flaps around the package, sealing the flaps and sealing a portion of the flaps to the bottom of the package, a sealing plate for further sealing the flaps to the bottom of the package, a continuously moving conveyer for pushing the package through the tucking units and into the sealing units, and a second conveyer for pushing the package from the sealing units and over the sealing plate for discharge from the machine.

20 14. A wrapping machine comprising, a pair of transversely spaced tucking units having means for folding and tucking side flaps of a package, a pair of side sealing units having means for stretching the flaps around the package, sealing the flaps and sealing a portion of the flaps to the bottom of the package, a continuously moving conveyer for pushing the package through the tucking units and into the sealing units, and a second conveyer for pushing the package from the sealing units and over the sealing plate for discharge from the machine, and drive means for synchronizing the operation of all of the parts to efficiently and quickly wrap a package.

25 15. A wrapping machine comprising, a pair of transversely spaced tucking units having means for folding and tucking side flaps of a package, a pair of side sealing units having means for stretching the flaps around the package, sealing the flaps and sealing a portion of the flaps to the bottom of the package, a sealing plate for further sealing the flaps to the bottom of the package, a continuously moving conveyer for pushing the package through the tucking units and into the sealing units, and a second conveyer for pushing the package from the sealing units and over the sealing plate for discharge from the machine, said tucking units and sealing units mounted on longitudinally extending angle bars, and means for adjusting said angle bars to change the spacing between said tucking and sealing units to accommodate various sizes of packages.

30 16. A wrapping machine comprising, a pair of transversely spaced tucking units having means for folding and tucking side flaps of a package, a pair of side sealing units having means for stretching the flaps around the package, sealing the flaps and sealing a portion of the flaps to the bottom of the package, a sealing plate for further sealing the flaps to the bottom of the package, a continuously moving conveyer for pushing the package

through the tucking units and into the sealing units, and a second conveyer for pushing the package from the sealing units and over the sealing plate for discharge from the machine, said tucking units and sealing units mounted on longitudinally extending angle bars, and means for adjusting said angle bars to change the spacing between said tucking and sealing units to accommodate various sizes of packages, said means including a single hand lever for effecting the width adjustment of all parts of said machine.

17. A wrapping machine comprising a pair of transversely spaced gathering rollers engaging the top portions of the package, a pair of transversely spaced tucking units having means for folding and tucking side flaps of a package, a pair of side sealing units having means for stretching the flaps around the package, sealing the flaps and sealing a portion of the flaps to the bottom of the package, a sealing plate for further sealing the flaps to the bottom of the package, a continuously moving conveyer for pushing the package through the tucking units and into the sealing units, and a second conveyer for pushing the package from the sealing units and over the sealing plate for discharge from the machine.

18. A wrapping machine comprising, a pair of transversely spaced tucking units having means for folding and tucking side flaps of a package, a pair of side sealing units having means for stretching the flaps around the package, sealing the flaps and sealing a portion of the flaps to the bottom of the package, a sealing plate for further sealing the flaps to the bottom of the package, means engaging the top of the package and biasing same towards the sealing plate, a continuously moving conveyer for pushing the package through the tucking units and into the sealing units, and a second conveyer for pushing the package from the sealing units and over the sealing plate for discharge from the machine.

19. A wrapping machine adapted to fold, tuck and seal the side flaps of a package comprising, means for folding and tucking the side flaps, means for stretching the side flaps to effect a tightly wrapped package and to partially seal the flaps to the bottom of the package, means for folding the flaps against the bottom and sealing them thereagainst, means for biasing the package against said folding and sealing means, and conveyer means for conveying the package along a rectilinear path during the wrapping operations.

20. A wrapping machine adapted to fold, tuck and seal the side flaps of a package comprising, means for folding and tucking the side flaps, a tucking and folding unit for tucking the side flaps and folding them downwardly, a side sealing and stretching unit for sealing the side flaps, stretching them over the package to effect a tight wrap, and sealing part of the flaps to the bottom of the package, a sealing and folding plate unit for further folding the flaps to the bottom of the package and sealing same thereto, means mounted in overlying relation to said sealing and folding plate unit for biasing the

packages thereagainst, said units being arranged in successive order so that the package may be moved along a rectilinear path through said units, and means for advancing the packages through said units.

5 21. A wrapping machine adapted to fold, tuck and seal the side flaps of a package comprising, means for folding and tucking the side flaps, gathering rollers mounted ahead of said tucking and folding unit and above said packages for gathering the material forming the side flaps and urging the side flaps into position to be received by said folding and tucking unit, a tucking and folding unit for tucking the side flaps and folding them downwardly, a side sealing and stretching unit for sealing the side flaps, stretching them over the package to effect a tight wrap, and sealing part of the flaps to the bottom of the package, a sealing and folding plate unit for further folding the flaps to the bottom of the package and sealing same thereto, means mounted in overlying relation to said sealing and folding plate unit for biasing the packages thereagainst, said units being arranged in successive order so that the package may be moved along a rectilinear path through said units, and means for advancing the packages through said units.

10 22. In a wrapping machine adapted to receive and complete the wrapping of a tray or card having edible substances thereon which is partially wrapped by a sheet of transparent heat-sealable material wherein side flaps extend laterally from opposite sides thereof, a horizontally extending support for receiving the partially wrapped item, conveyer means for continuously advancing the item along said support with the axes of the flaps extending transverse the direction of conveyer travel, a folding and tucking unit along said support adapted to fold and tuck the side flaps as they pass therethrough, and a side sealing unit for sealing said side flaps and sealing a portion of the flaps to the bottom of the item, said side sealing unit including means for engaging the side flaps and stretching them about the item to effect a tightly wrapped package.
